UNITED STATES PATENT OFFICE

JAMES W. YATES, OF CINCINNATI, OHIO, ASSIGNOR TO THE CINCINNATI TIME RECORDER COMPANY, OF CINCINNATI, OHIO, A CORPORATION OF OHIO

TIME RECORDER

Application filed May 15, 1920. Serial No. 381,528.

My invention relates to workmen's time recorders and has as its object the provision of means for distinctively printing all overtime records, in such a way as to prevent 5 tampering by dishonest workmen.

More specifically it is my object to provide in connection with the time printing means of time recorders for the printing of records during periods of overtime, in a different ink 10 for normal records, and furthermore to print a slug alongside of the overtime records.

It has been found possible to cheat machines which print overtime records in red ink, by inserting a piece of carbon paper with 15 the time card, so arranged as to block off the printing ribbon, and give a registration which is sufficiently like normal registrations on the card to avoid detection. Where a slug is printed, however, together with a distinguishing color of ink for the time record, it 20 is not believed possible to obtain a false imprint. It would require that the falsifier should employ an impervious insert along with his card to prevent the slug from printing, and a carbon paper as well, to correct the distinguishing color. I have been unable to 25 do both of these things myself and do not believe that it would be even remotely possible to accomplish them.

30 I attain the objects of my invention by that certain construction and arrangement of parts to be hereinafter more specifically pointed out and claimed.

In the drawings:

35 Figure 1 is a front elevation of the portions of a time recorder with which my invention is concerned.

Fig. 1^A is a detail of the ribbon supporting means.

40 Figure 2 is a side elevation of the said parts.

Figure 3 is a similar view to Figure 2, showing the parts when printing an irregular registration.

45 Figure 4 is a detail of the irregular time control disks and pawls.

Figure 5 is a plan view of a time card with time registrations imprinted thereon.

50 My time recorder mechanism is no different from that of any time recorder, except

as concerns the provision of means for shifting a printing ribbon during certain periods of time, and at the same time shifting an arm to a position alongside of the time wheels, this arm carrying a type face, which 55 will be impressed upon the card.

In time recorders of the type in use at the present day, the normal structure comprises time wheels rotated by a clock, a platen in the form of a rubber faced hammer which is 60 energized and tripped so as to fly against the face of a card, a card tray in which a card is held, and a printing ribbon interposed between the time wheels and the card. The time wheels have type upon them for the 65 hours and minutes of the day.

The mechanism for supplying the energizing force to the selective devices for shifting the ribbon and raising the slug type face to printing position alongside of the time 70 wheels is energized by the manually moved handle that works the usual platen. The mechanism for controlling the result of the applied force of the manual printing handle is energized by the clock, and in order to 75 permit of the handle being depressed fully at times when the clock operated mechanism prevents the operation of the said selective devices, the manual handle is connected to the selective mechanism itself by means of a 80 spring.

The time clock (not shown) drives the vertical shaft 4, being coupled to this shaft by the usual coupling. On the shaft is a worm 3 which drives the pinion of a large 85 circular disk 1. This disk or dial is calibrated for hours and revolves once in 24 hours. It has circumferentially arranged interrupted slots 2 therein. In the slots are lifting fingers 8, held in place by screws, so 90 as to be adjustable in the slots. A lever 6 mounted on a standard 5 of the machine has a depending contact plate or finger 7, which will be engaged by the finger 8, so as to lift and drop the lever as the disk or dial 1 revolves. The raising and dropping of the lever serves to lift and drop a pawl to be described. This pawl rotates the element 95 that inhibits or permits the irregular record shift of the machine.

I will first describe the manually operated means which unless inhibited would operate the irregular record distinguishing devices every time the platen handle is manipulated, to effect a printing on a card. A rock shaft 12 is provided for the machine, on which rock shaft is a lever 11, pivotally fulcrumed on the said shaft. Also on the shaft 12 is an arm 13 that is fast thereon and serves to rock the shaft. The printing platen operating handle 9, in addition to its usual connections, has connected thereto a rod 10 which is pivotally secured to one end of the lever 11. The other end of the lever 11 is connected by a spring 15 with the lever 13, so that when the handle is depressed the shaft 12 will rock unless its rocking is prevented, in which case the spring 15 will extend to permit full operation of the printing platen operating handle.

I have merely indicated at 28, the usual printing ribbon retaining element by means of which in many time recorders, the printing ribbon is shifted crosswise to change colors. I have indicated at 24 the usual time printing wheels. I have also indicated a type face 22, termed by me a "slug" which is to be moved to a position alongside the printing point of the time wheels, during irregular registrations. By my mechanism I have the printing ribbon holder upwardly and shift the type face 22 upwardly, every time the printing handle is depressed unless this motion is prevented by mechanism controlled from the shaft 12.

In order to operate these two devices I provide a rock shaft 19 mounted above and forwardly of the shaft 12. On the shaft 19 is an arm 20, connected to a metal piece 21. This piece has a forked lower end that engages slidably over a rod 23 on which the time wheels are revolvably mounted. One portion of the fork has the type face 22 thereon. When the shaft 19 is rocked the arm 20 is tilted up, the piece 20 lifted, and it slides up as guided by the rod 23, until its type face comes on a line with the printing point. The two positions of the type face are shown in Figures 2 and 3.

In order to shift the ribbon I provide a lever 25, that is fulcrumed intermediate its ends on the rod 23. One of its ends engages the ribbon shift device 28. The other end of the lever 25 is pivoted to a link 26, and the link pivoted at its upper end to an arm 27 also on the shaft 19. Thus when the shaft 19 is rocked the link 26 is lifted and the ribbon shift moved up to change the printing surface of the ribbon from one color to another. It is not believed to be necessary to describe the usual two color ribbon and ribbon shift, as every typewriter and many recorders are equipped with them.

The operating devices by means of which the rocking of the shaft 12 will rock the shaft

19 are a hook-shaped plate 16 mounted fast on the shaft 12, a link 17 connected to the free end of the plate 16, and an arm 18 fast on the rock shaft 19, and connected to the link 17.

The inhibiting devices serve to prevent the operation of the shaft 19 by opposing the motion of the plate 16. To accomplish this two disks are provided, as shown at 33 and 41. These disks are coupled together and are mounted over a suitable rod in the machine frame. There are teeth around the peripheries of the two disks, there being twice as many teeth on the disk 33 as on the disk 41. The plate 16 lies beneath the disk 41, and has a lug or tooth 43 on the upper surface. When the disk 41 is moved to a position with a space between teeth presented to the lug 43, then the depression of the printing operating handle will be able to rock the plate 16 and accomplish an irregular registration indication by means of printing in an off color and also printing the type face 22, on an inserted card. When a tooth of the disk 41 is presented to the lug 43, the piece 16 cannot rock.

The disk 33 is an operating disk, and is revolved by the raising and lowering of the lever 6 by means of the fingers on the dial 1.

The lever 6 has a link 30 connected to its outer end, which link is connected to one end of a plate 31, that is pivotally supported on the rod 23. The plate 31 has an overthrow preventing tooth 34 therein that engages in between the teeth of the disk 33. Pivoted at the free end of the plate 31 is a pawl 32, which follows the edge of the toothed disk 33, being held by gravity and with a spring 32a.

On a stud 36 of the frame is a pawl 37, which has a movement preventing tooth 40 thereon that meshes with the teeth of the disk 33. This pawl is kept in position by a counterweight 38 secured to its lower end, while the upper end is urged toward the edge of the disk 33.

Means is provided whereby when the pawl 32 is lifted this not only elevates the tooth 34, but also will move the pawl 37 so that its tooth 40 rises from mesh with the teeth of the disk 33. This structure comprises a pin 39 on the upper tip of the pawl 37, which pin lies in the path of the pawl 32. When the pawl 32 is lifted its end passes above the pin 39. It is then free to be pulled into mesh with a tooth of the disk 33, and is permitted to fall thereby advancing the disk one tooth in rotation. There is a hook or lip 33a on the lower edge of the pawl 32, that in the motion of advance moves between the disk 33 and the said pin 39, thereby lifting it up, and pulling the tooth 40 out of mesh so that the disk can rotate. When the pawl 33 has finished its downward movement the lip 33a will have moved past the pin 39, so that the pawl 37 can be pulled back into mesh again by its weight. When the pawl 33 rises again the lip 33a passes over the top of the pin 39, per-

mitting the disk 33 to be held against movement by the tooth 40 on the pawl 37.

When the fingers 8 lift the lever 6, this raises the connections described and lifts the pawl 32, and when the fingers pass under the plate 7 on the lever 6, the pawl 32 is permitted to fall. Every other time that this lifting and dropping occurs, the plate 16 is permitted to rise sufficiently to move the ribbon holder and shift the slug type face into printing position.

Thus the fingers 8 define by their spacing on the dial 1 alternate irregular record and regular record periods, which can be arranged for any desired periods of the day or night, as per the mechanism described.

Having thus described my invention, what I claim as new and desire to secure by Letters Patent, is:—

1. In a time recorder having time printing means the combination of means for shifting a two color printing ribbon to bring the desired color opposite the printing point of the printing means, a distinguishing type face for irregular registrations, means for shifting the same into position opposite said printing point, a lever, a clock shaft and mechanism driven thereby, and mechanism actuated by the said lever and controlled by the clock operated mechanism, for simultaneously operating the said two shifting means, whereby both a distinguishing color and a distinguishing type face is impressed upon the operator's card.

2. In a time recorder having time printing means the combination of means for shifting a two color printing ribbon to bring the desired color opposite the printing point of the printing means, a distinguishing type face for irregular registrations, means for shifting the same into position opposite said printing point, a lever, a clock shaft and mechanism driven thereby, and mechanism actuated by the said lever, and controlled by the clock operated mechanism, for simultaneously operating the said two shifting means, whereby both a distinguishing color and a distinguishing type face is impressed upon the operator's card, said power means comprising a platen operating lever under manual control.

3. In a time recorder having time printing means the combination of means for shifting a two color printing ribbon to bring the desired color opposite the printing point of the printing means, a distinguishing type face for irregular registrations, means for shifting the same into position opposite said printing point, a lever, a clock shaft and mechanism driven thereby, and mechanism actuated by the said lever and controlled by the clock operated mechanism, for simultaneously operating the said two shifting means, whereby both a distinguishing color and a distinguishing type face is impressed upon

the operator's card, said clock operated mechanism comprising a step by step rotary member laying in the path of the power means actuated mechanism, and provided with members adapted on alternate step by step movements to oppose the movement of the said mechanism, and on the intermediate step by step movements to permit the said mechanism to move freely.

4. In a time recorder having time printing means the combination of means for shifting a two color printing ribbon to bring the desired color opposite the printing point of the printing means, a distinguishing type face for irregular registrations, means for shifting the same into position opposite said printing point, a lever, a clock shaft and mechanism driven thereby, and mechanism actuated by the said lever and controlled by the clock operated mechanism, for simultaneously operating the said two shifting means, whereby both a distinguishing color and a distinguishing type face is impressed upon the operator's card, said clock operated mechanism comprising a pair of disks having teeth thereon, those of one disk spaced twice the distance of those on the other disk, said lever actuated mechanism having a member adapted to contact with the said other disk, or to pass between its teeth dependent upon its position, and means driven by the clock shaft and adapted to advance the first said disk step by step, so that upon alternate step by step movements of the first disk, the second disk will inhibit the movement of the power means actuated mechanism by interposing a tooth in its path.

5. An irregular record distinguishing mechanism for time recorders comprising a member to be moved, an operating lever connected to said mechanism by means including a member whose movement is to be inhibited or permitted, and a clock shaft and mechanism operated thereby comprising a pair of disks connected to each other, one having its teeth spaced twice the distance of the other, driving means for the one disk to advance it step by step by clock shaft, said member whose movement is to be inhibited having a tooth so located as to engage the teeth of the other of said disks or pass between the teeth, in which latter instance the movement is not inhibited, as and for the purpose described.
